RADIO TELEPHONE SET

Per Erik Edward Heribertson, Lidingo, Sweden, assignor
to International Standard Electric Corporation, New
York, N.Y.

Filed Oct. 20, 1969, Ser. No. 19,621

Term of patent 14 years

Int. Cl. D14—03

U.S. Cl. D26—14

FIG. 1

FIG. 2

FIG. 3

FIG. 4

FIG. 5

FIG. 7

FIG. 6

FIG. 8

FIG. 9

FIG. 10

FIG. 11

FIG. 12

FIG. 14

FIG. 13

FIG. 1 is a front perspective view of a radio telephone set showing my new design;

FIG. 2 is a top plan view thereof with the handset omitted for ease of illustration;

FIG. 3 is a front elevation thereof;

FIG. 4 is a side elevation as seen from the right of FIG. 1;

FIG. 5 is a rear elevation thereof;

FIG. 6 is a bottom plan view thereof;

FIG. 7 is a side elevation as seen from the left of FIG. 1;

FIG. 8 is a front perspective view of a modified embodiment of the radio telephone set shown in FIG. 1;

FIG. 9 is a top plan view thereof;

FIG. 10 is a front elevation thereof;

FIG. 11 is a side elevation as seen from the right of FIG. 8;

FIG. 12 is a rear elevation thereof;

FIG. 13 is a bottom plan view thereof; and

FIG. 14 is a side elevation as seen from the left of FIG. 8.

The broken lines representing conventional indicia is shown for illustrative purposes only and forms no part of the claimed design.

I claim:

The ornamental design for a radio telephone set, substantially as shown and described.
